United States Patent Office

Des. 183,927
Patented Nov. 18, 1958

183,927

BOAT

Robert R. Hammond, Austin, Tex., assignor to Standard
Glass Products, Austin, Tex., a corporation of Texas

Application October 16, 1957, Serial No. 48,115

Term of patent 14 years

(Cl. D71—1)

Fig. 2.

Fig. 3.

Fig. 1 is a perspective view taken from above and from the front of a boat embodying the new design;

Fig. 2 is a side elevation thereof; and

Fig. 3 is a top plan view of the boat.

The dominant features of the design reside in the portions shown in full lines.

I claim:

The ornamental design for a boat, substantially as shown and described.
